CLAIM

The ornamental design for an illuminated loudspeaker, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of an illuminated loudspeaker, showing the new design.

The dash-dot broken lines represent the boundaries of the claimed design and form no part of the claimed design. The evenly spaced broken lines and the gray masked areas depict environment and form no part of the claimed design.
